UNITED STATES PATENT OFFICE.

WILLIAM T. ATWOOD, OF MELROSE, MASSACHUSETTS, ASSIGNOR TO FREEMAN BRICK CLEANING MACHINE COMPANY, OF BOSTON, MASSACHUSETTS, A CORPORATION OF MASSACHUSETTS.

BRICK-CLEANING MACHINE.

Application filed May 8, 1923. Serial No. 637,498.

To all whom it may concern:

Be it known that I, WILLIAM T. ATWOOD, a citizen of the United States, residing at Melrose, in the county of Middlesex and 5 State of Massachusetts, have invented new and useful Improvements in Brick-Cleaning Machines, of which the following is a specification.

The present invention relates to machines 10 for cleaning used brick by removing fragments of mortar adhering to the sides of the brick and reducing the surfaces of the brick to approximate planes, and to approximate parallelism with one another as to opposite 15 faces of the brick. More particularly it is an improvement in machines of the type shown in the patent to James F. Freeman No. 1,033,573 dated July 23, 1912.

The principal object of the invention is 20 to provide a cleaning head of improved construction enabling the individual cutters to be more readily assembled with the head, in staggered relation with each other and to be removed and replaced when broken, without 25 out the necessity of removing the cutter head from its shaft.

The preferred construction of the present 30 improvements is shown in the accompanying drawings and described in the following specification.

In the drawings,—

Figure 1 is a face view of a cutter-carrying head or cleaning head embodying the invention, with a part of the cover plate broken away.

Figure 2 is an end or edge view of such head shown partly in elevation and partly in radial section.

Figures 3 and 4 are detail cross sectional 40 views taken on line 3—3 and on line 4—4, respectively, of Figure 2.

Figure 5 is a perspective view of one of the cutter units shown by the preceding figures.

The machine as a whole may comprise a 45 frame or chassis of any suitable construction, mounted on wheels, as shown by the Freeman patent above mentioned.

A motor of any suitable character, as an 50 internal combustion engine, an electric motor, or one of any other sort, may be employed to drive the cleaning head hereinafter described, the motor being mounted on the frame and suitably connected with a

driving shaft to which the carrying member 55 of the cleaning head hereinafter described is secured, said shaft being journaled in bearings above and supported by the frame.

My new form of cleaning head comprises a circular carrying member including a central hub 10, attachable to a driving shaft 11, a body portion 12, extending outward from and surrounding the hub, and spaced apart outer and inner projections 12^a and 12^b, preferably annular flanges concentric 60 with the hub and projecting outward from the body portion, said projections being spaced apart to permit the interposition between them of the radially arranged shafts hereinafter described.

The outer projection 12^a is provided with outer notches 13, and the inner projection 12^b is provided with inner notches 13^a. Said notches have open sides on the outer faces of the projections, and closed ends forming 70 abutments for the opposite ends of shafts 20. The open sides of the notches permit the insertion of the shafts laterally into the notches, and the closed ends of the notches prevent endwise movement of the inserted 75 shafts. The outer projections are made sufficiently thick and strong to support the shafts against the tendency of centrifugal force to displace them endwise when the head is rotated at a high speed.

The shafts 20 extend radially, or approximately so, from the inner to the outer notches. On the shafts 20 are loosely mounted cutting tools or units which include serrated or star wheels, adapted to remove mortar from a brick by rolling in contact therewith, as described by the Freeman patent. I prefer to make each unit by assembling two star wheels 23 23, and an interposed disk or washer 24, as shown by 90 Figure 5. These wheels and washer, when moved to place on a shaft 20, are adapted to rotate freely on the shaft.

Each shaft is provided with a plurality of cutter units, these being spaced apart on 100 the shaft, as hereinafter described.

My improved cleaning head comprises also confining means separably mounted on the carrying member, and including elements adapted to confine the shaft ends in the grooves 13 and 13^a, and elements adapted to confine the cutter units spaced apart from each other on the shafts.

In the embodiment of the invention here shown, said elements are parts of an annular plate 25, seated on the outer faces of the projections 12^a and 13^a, and separably secured to the projections by means such as screws 28. The outer marginal portion 25^a of the plate constitutes a cover for the open sides of the outer notches 13. The inner marginal portion 25^b of the plate constitutes a cover for the open sides of the inner notches 13^a. Said covers extend across the portions of the shafts 20 inserted in the notches and prevent lateral displacement or removal of the shafts.

15 The elements which confine the cutter units spaced apart on the shafts 20 are spacers 26, provided in this instance, by forming spaced apart openings or slots 27 in the plate 25, through which portions of 20 the cutter units project, the spacers 26 being interposed between adjacent units.

25 The spacers are adapted and arranged to maintain the cutter units on any shaft 20, in staggered relation to the units on an adjacent shaft, as shown by Figure 1, so that the units of each shaft form grooves in a mortar facing which are between the grooves formed by the units of an adjacent shaft.

30 The shafts 20 are relatively long and extend from points near the hub to points near the periphery of the carrying member. Between these shafts are other shafts 21, which are similar, but shorter, and occupy the spaces between adjacent shafts 20, near the periphery of the carrying member. The outer ends of the shafts 21 are contained in some of the notches 13, in the outer projections 20, and the inner ends are 35 contained in notches 13^b, similar to the inner notches 13^a and formed in bearing lugs 22, formed on the body portion 12 of the carrying member. Intermediate notched lugs or chairs 22^a may be provided, to oppose the bending stress to which the longer 40 shafts 20 are subjected.

45 It will be seen that when the cover elements 25^a and 25^b are removed, the shafts and the cutter units strung thereon, may 50 be installed in and removed from the carrying member, without withdrawing the shafts from the cutter units, and that when the shafts are installed, they are adequately supported by the outer projection of the 55 carrying member against endwise displacement due to centrifugal force.

60 The inclusion of the cover elements 25 and 25^a, in a single plate 25, which also includes the spacers 26, according to the preferred embodiment of the invention, enables the plate to constitute the sole means for separably confining the cutter-holding shafts in the notches, and for maintaining the proper spacing between the cutter units, said elements being quickly removable and attach-

able to permit the removal of worn out and broken cutters and the substitution of others therefor.

The ends of the cutter-bearing shafts constitute shoulders arranged to cooperate with 70 those portions of the projections on the carrying member which form the closed ends of the notches.

The plate 25 may be made in a number of segments, each separately secured by its 75 own attaching screws or the like and detachable separately from the others, as clearly shown in Figure 3. Thus when replacement of a single cutter, or of a few 80 adjacent cutters, etc., is all that is needed by way of repair, only that part of the plate which overlies the damaged or useless parts need be removed, and the other cutters and shafts may remain undisturbed.

Even in the first assemblage it is much 85 easier to apply a plate consisting of a number of separate segments than a cover of one piece which overlies the whole head, and with the openings in which all of the cutter units must be registered at the same 90 time.

Evidently in place of providing the notches for the shafts 20 in continuous projections 12^a and 12^b, discontinuous notched lugs like the lugs 22 may be used, adequate 95 means being provided for securing the shafts in the notches of said lugs. Other modifications in structure and arrangement of the several parts may also be made without departing from the scope of the protection which I claim.

What I claim and desire to secure by Letters Patent is:

1. In a brick-cleaning machine, a rotary 105 cleaning head comprising a circular carrying member including a central hub attachable to a driving shaft, a body portion extending outward from and surrounding the hub, and spaced apart inner and outer projections arranged concentric with the hub and projecting outward from the body portion, the projections being provided with outer and inner notches having open sides and closed ends, radially arranged shafts 110 inserted at their ends in the open sides of said notches and confined against endwise movement by the closed ends thereof, rotatable cutter units loosely mounted on said shafts, there being a plurality of units on each shaft, and confining means separably mounted on the carrying member and including covers closing the open sides of the notches, to prevent lateral outward movement of the shafts, and spacers interposed 115 between the cutter units, to maintain the same spaced apart on the shafts, said spacers being adapted and arranged to maintain the units on any shaft in staggered relation to the units on an adjacent shaft.

2. In a brick cleaning machine, a clean-

- ing head comprising a disk-like body with spaced apart projections from one side thereof having shaft bearing notches, radially arranged shafts located in said notches and having shoulders arranged to cooperate with said projections to limit endwise displacement of the shafts, a cover overlying said projections and being detachably fastened to said body so as to retain the shafts in place, and rotatable cutter units loosely mounted on the shafts, the cover having openings in parallel alinement with the several shafts through which said cutters project.
3. In a brick cleaning machine, a cleaning head comprising a disk-like body with spaced apart projections from one side thereof having shaft bearing notches, radially ar-
- ranged shafts located in said notches and having shoulders arranged to cooperate 20 with said projections to limit endwise displacement of the shafts, a cover overlying said projections and being detachably fastened to said body so as to retain the shafts in place, and rotatable cutter units loosely 25 mounted on the shafts, the cover having openings in parallel alinement with the several shafts through which said cutters project and being made of a plurality of segments each independent of the others and 30 independently and detachably secured to the body of the head.

In testimony whereof I have affixed my signature.

WILLIAM T. ATWOOD.
